CLAIM

The ornamental design for a fishing rod holder for a fishing rod locker, as shown and described.

DESCRIPTION

FIG. 1 is a perspective view of a fishing rod holder for a fishing rod locker, showing our new design;

FIG. 2 is a left side elevation thereof, the opposite side being a mirror image;

FIG. 3 is a rear elevation view thereof, the front being a mirror image;

FIG. 4 is a top plan view thereof; and,

FIG. 5 is a bottom plan view thereof.
